SERVING TRAY

Kenneth C. Netzler, Cincinnati, Ohio

Application October 5, 1953, Serial No. 27,076

Term of patent 14 years

(Cl. D44—10)

To all whom it may concern:

Be it known that I, Kenneth C. Netzler, a citizen of the United States, residing at Cincinnati, county of Hamilton, and State of Ohio, have invented a new, original, and ornamental Design for a Serving Tray, of which the following is a specification, reference being had to the accompanying drawings, forming part thereof.

Fig. 1 is a top plan view of a serving tray, showing my new design.

Fig. 2 is a sectional view taken on line 2—2 of Fig. 1.

Fig. 3 is a sectional view taken on line 3—3 of Fig. 1.

Fig. 4 is a perspective view of the serving tray.

I claim:

The ornamental design for a serving tray, as shown.
